CLASSIFIER

Charles Harrell, Wateree, S. C., assignor of one-third to Jefferson B. Bates, Wateree, S. C., and one-third to Harry E. Dixon, Columbia, S. C.

Application June 28, 1933, Serial No. 678,069

7 Claims. (Cl. 210—51)

This invention relates to certain new and useful improvements in classifiers for separating solids from liquids and is capable of, and intended for, use in any art in which this function is to be performed.

The principle of my invention involves the opposing of the resistance of the accumulating mass of solids or semi-solids to a source of stored energy whereby when such resistance overcomes the opposed power of said stored energy mechanism will be caused to operate to discharge some of said accumulated solids or semi-solids, thereby removing the resistance of the latter, whereupon the power of said stored energy will reversely operate the mechanism to stop such discharge of such solids or semi-solids and restore the parts to their initial position.

The primary objects of my invention are to provide dependable intermittently operating automatic means for opening and positively and completely closing the discharge valve of a settling tank or hopper; to control the timing of the opening and closing of said valve by the rising and falling level of the accumulated solids or semi-solids in the tank or hopper whereby the discharge of liquid with the solids may be effectually guarded against; and, considered more narrowly, to provide means whereby the power necessary to operate the automatic intermittent solids discharge mechanism may be obtained from the separately discharged liquids.

One practical embodiment of the invention is illustrated in the drawings wherein:

Figure 1 represents a top plan view of a classifier embodying my invention;

Figure 2, a vertical cross sectional view on the line 2—2 of Fig. 1;

Figure 3, a side elevation illustrating the harnessing of the power of the discharged liquids to operate the automatic intermittent operating mechanism;

Figure 4, an enlarged detail fragmentary section through the differential assembly and adjacent portions to illustrate the drive; and

Figure 5, a fragmentary view of a modification wherein an electric motor acting directly on drive shaft 1 is substituted for the drive means illustrated in previous views.

Referring now in detail to the drawings, A designates the supply chute through which liquid with solid matter suspended therein is introduced into the hopper B from which it escapes by the discharge C into the discharge flume D. The sides of the hopper B converge downwardly to a central discharge opening which is provided with

a downwardly presented cone form valve seat E to receive and seat the upper cone face of a closure plug or valve F connected to the lower end of a vertical rod G.

A suitable housing having tubular arms 2 and 9 and the differential housing portion 4 extends across the top of the tank or hopper B and is secured thereto against relative movement in any suitable manner as illustrated.

The drive shaft 1 extends through the arm 2 and is suitably supported therein by bearings, not shown, for rotation in respect thereto and has the beveled gear 3 of the differential housing mounted on its inner end to turn therewith.

The shaft 5 is disposed perpendicular to the common axis of the shafts 1 and 8 and extends through the short tubular arm 6 wherein it is supported by suitable bearings, not shown, for rotation therein. A beveled gear 7 mounted on the upper and inner end of the shaft 5 to turn therewith is in mesh with the ring gear 13. The ring gear 13 is secured in usual manner to the differential gear case 12 in which are radially mounted the differential pinions 11 respectively in mesh with each of the beveled gears 3 and 10 of the differential assemblage.

A supporting frame, beam or bar 15, preferably of elongated U shape so as to have its medial portion raised appreciably above the shafts 1 and 8 and so above the upper edge of the tank or hopper B, is secured in any desired or usual manner to the latter, and a beam lever having arms 14 and 16 is pivotally mounted thereon adjacent its medial portion by any suitable means, such as a pin 18, and the upper end of the valve stem or rod G is bifurcated to receive the arm 14 of said lever and is connected thereto in any suitable manner to move upward and downward therewith, as for instance by means of a pivot pin 17 passing through the said bifurcations and the interposed portion of the arm 14.

Any suitable means for applying restored energy to the said beam lever to cause the free end of its arm 14 to move away from the shaft 8 may be employed. In the embodiment illustrated a weight 19 applied to the arm 16 is employed for this purpose.

A blade or paddle 20 is secured to the lower end of the paddle shaft 5 to turn therewith.

A cable 21 secured to the eye 23 of the arm 14 of the beam lever is attached to the spool or drum 22 secured to the end of the shaft 8 to turn therewith. Shaft 8 extends in housing arm 9 and bevel gear 10 is secured to the inner end of shaft 8 to turn therewith.

The operation is briefly as follows. So long as the highest level of the accumulated solids or semi-solids remains below the paddle 20 there is no resistance to the free turning of said paddle 5 20 in the liquid and hence no resistance to the free rotation of the paddle shaft 5, whereas the weight 19 acting through the leverage of said beam lever, the cable 21 and spool or drum 22, will offer a resistance to the rotation of the shaft 10 8 with the drive shaft 1, so that the pinions 11 as driven by the beveled gear 3 will ride around over the beveled gear 10 and in so doing will carry with them the differential gear case 12 and ring gear 13, which will drive the beveled gear 7 15 mounted on paddle shaft 5 to rotate therewith, so that under these circumstances the paddle shaft 5 will rotate while pulley or drum shaft 8 will remain stationary. As the solid or semi-solid material accumulates beyond this point and rises 20 above the lower edge of the paddle 20 it will offer an increasing resistance to the turning of the latter until it reaches approximately the level indicated at X, at which point the resistance offered by the mass of accumulated solids or semi- 25 solids will be greater than the force exerted by the weight 19, so that the pinions 11 will cease to roll over or around the beveled gear 10, but instead will couple the latter with the drive shaft 1, whereby shafts 1 and 8 will turn together, 30 resulting in the cable 21 being wound up on the drum or spool 22 and so pulling the end of arm 14 of the beam lever down and thus shoving the valve rod or stem G down to force the valve F out of the discharge opening E so that the accumulated 35 solids or semi-solids may discharge therethrough. As soon as the solids or semi-solids start to discharge, their level in the hopper or tank B starts to fall and so progressively relieves the resistance to the rotation of the paddle 20 and 40 as such resistance is removed from said paddle 20 the force of the power of the weight 19 overcomes the decreasing resistance transmitted by the paddle 20, depressing the arm 16 of the beam lever to its initial position, so raising the arm 14 of said 45 lever and firmly and positively pulling the valve or plug F back to its initial seated closed position to prevent further discharge of the solids or semi-solids until the latter have again accumulated, so that the level of the accumulated solids or semi- 50 solids never drops below an approximate selected level such as Y, and never rises above an approximate selected level indicated at X.

The weight 19 is mounted on the arm 16 so as to be slidably endwise thereof and may be 55 locked in any desired position of adjustment thereon by any suitable means, such as a binding or friction screw 24 passing through a portion of the weight 19 and engaging against the side of said arm 16, in accordance with usual well known 60 practice. By reason of this adjustment the mechanism may be very delicately or closely set.

The shaft 1 may be driven by an suitable means. Where there is a large flow of liquid, as for instance the discharge of water with its suspended sand from a gravel washer, the separated water as discharged from the classifier may be used to furnish the power to drive the shaft 1, and in Figs. 1, 2 and 3 I have illustrated an embodiment wherein this is done. A shaft 26 is mounted 65 in suitable bearings, not shown, on the lower end of the liquid discharge flume D, a paddle wheel 25 being keyed to this shaft 26 to turn therewith and being driven by the liquid as discharged from said flume. A sprocket wheel 27 70 secured to the outer end of said shaft 26 serves

to drive a sprocket chain 28 which in turn drives a sprocket wheel 29 secured to a shaft 30 to turn therewith, said shaft being mounted in suitable bearings in a bracket 31 and having mounted on its outer end to turn therewith a gear 32 which in turn meshes with a gear 33 mounted on the outer end of shaft 1 to turn therewith.

In the modification illustrated in Fig. 5, the construction and operation are the same as in the preferred form except that instead of the drive means therein illustrated for the shaft 1 I substitute an electric motor 34 operating directly on shaft 1 to rotate the same, said motor 34 being mounted in any suitable manner, as by a bracket or support 35 suitably secured in a usual manner to the side of the tank or hopper B or any other suitable fixed support.

Obviously any other and suitable means of driving the shaft 1 may be substituted for either of the means herein illustrated.

It will be apparent that the beam lever having arms 14 and 16 may be substituted by a quite different element or mechanism so long as the function is preserved, and this observation applies also as to the cable 21, spool or drum 22 and 100 the weight or source of stored energy 19. Similarly the type of valve seat or discharge opening 3, the type of valve or plug F and the rod or valve stem G may be replaced by any other suitable type of mechanism functioning to open and 105 close a discharge opening in any manner.

Likewise, the shafts 1, 5 and 8 may be replaced by any other means capable of functioning to the same general end and any power transmitting or connecting means capable of transmitting power from a drive element or mechanism to one driven element or mechanism, and at the same time either turning freely with relation to a second selectively driven element or coupling itself thereto according as resistance to 110 the turning or movement of the first mentioned driven element or mechanism is absent or is built up to a point where the coupling action is brought into play, may be employed in place of the differential assembly.

In other words, in this application I have merely illustrated several of the present preferred embodiments of my invention simply by way of illustration of the practice thereof, as by law required. However, the invention is capable 125 of being embodied in a great many different forms, the exact form of embodiment being a matter of no particular importance and the various detail elements being of no importance whatsoever, except insofar as their presence in a particular embodiment may be necessary to the proper functioning of that particular embodiment or preferred for use in that particular embodiment.

Having thus described my invention, what I 135 claim as new and desire to secure by U. S. Letters Patent is:

1. A classifier for separating liquids and solids or semi-solids and having a settling tank with inlet and overflow means at the top, a discharge 140 orifice at the bottom, a plug for closing said orifice, and a rod connected to said plug for moving the same to open or to close said orifice, in combination with a drive shaft, means for constantly driving the same, a paddle shaft extending down 145 into said tank, a paddle rigidly secured to the lower end of said paddle shaft at such level as to be subject to the resistance to its turning of the said solids or semi-solids when they accumulate in said tank above a given point, a lever pivotally 150

- mounted intermediate its ends on a fixed object, a weight slidably adjustably mounted on one arm of said lever, means for securing said weight in any adjusted position, means pivotally connecting 5 said rod to the other arm of said lever, an intermittently driven shaft, a drum secured to said intermittently driven shaft, a cable connected to the last mentioned arm of said lever and to said drum, a bevel gear connected to the upper end 10 of said paddle shaft to turn therewith, and a differential gear interposed between said drive shaft and intermittently driven shaft to intermittently couple the latter to the former, and having a continuously driven ring gear meshing with and constantly driving said bevel gear on said paddle shaft. 15 4. A discharge element operating mechanism for a classifier having a settling tank with inlet and overflow means at the top, a discharge orifice at the bottom and a closure element for closing said orifice, said mechanism comprising a drive shaft, means for constantly driving the same, a paddle shaft extending down into said tank, a paddle rigidly secured to the lower end of said paddle shaft at such level as to be subject to the resistance to its turning of the said solids or semi-solids when they accumulate in said tank above a given point, a weight, connections between said closure element and said weight whereby the latter acts to exert power tending to move said closure element into, and hold it in, position closing said orifice, an intermittently driven shaft, means connecting said weight and said intermittently driven shaft, a bevel gear connected to the upper end of said paddle shaft to turn therewith, and a differential gear interposed between said drive shaft and intermittently driven shaft to intermittently couple the latter to the former to lift said weight and move said closure element to open said orifice, and having a continuously driven ring gear meshing with and constantly driving 20 said bevel gear on said paddle shaft. 5. A classifier having a settling tank with inlet and overflow means at the top, a discharge orifice at the bottom and a plug for closing said orifice, in combination with a drive shaft, means for constantly driving the same, a paddle shaft extending down into said tank, a paddle rigidly secured to the lower end of said paddle shaft at such level as to be subject to the resistance to its turning of the said solids or semi-solids when they accumulate in said tank above a given point, a lever pivotally mounted intermediate its ends on a fixed object, a weight mounted on one arm of said lever, means pivotally connecting said rod to the other arm of said lever, an intermittently driven shaft, a drum secured to said intermittently driven shaft, a cable connected to the last mentioned arm of said lever and to said drum, a bevel gear connected to the upper end of said paddle shaft to turn therewith, and a differential gear interposed between said drive shaft and intermittently driven shaft to intermittently couple the latter to the former and having a continuously driven ring gear meshing with and constantly driving said bevel gear on said paddle shaft. 25 6. A discharge plug operating mechanism for a classifier having a settling tank with inlet and overflow means at the top, a discharge orifice at the bottom and a plug for closing said orifice, and a rod connected to said plug for moving the same to open or to close said orifice, said mechanism comprising a drive shaft, means for constantly driving the same, a paddle shaft extending down into said tank, a paddle rigidly secured to the lower end of said paddle shaft at such level as to be subject to the resistance to its turning of the said solids or semi-solids when they accumulate in said tank above a given point, in combination with a lever pivotally mounted intermediate its ends on a fixed object, a weight mounted on one arm of said lever, means pivotally connecting said rod to the other arm of said lever, an intermittently driven shaft, a drum secured to said 30 70 75 80 85 90 95 100 105 110 115 120 125 130 135 140 145 150

variations in the degree of resistance offered to the movement of said driven means in said tank whereby when said resistance equals the applied power of said source of energy said driven element will be coupled to said drive element and driven thereby to move said plug to open position and when said resistance drops below said applied power said driven element will be uncoupled from said drive element and said source of energy will act to move said plug to closed position and hold it in such position until its applied power is again equaled by said resistance.

7. A solids discharge element operating mechanism for a classifier having a settling tank with inlet and overflow means at the top, a discharge orifice at the bottom and an element for closing said orifice, said mechanism comprising a drive element, and means driven by said drive element and having movement in said settling tank and being subject to the resistance of said solids or semi-solids when they accumulate in said tank above a given point, in combination with a source

of energy, connections between said closure element and said source of energy whereby the latter acts to exert power tending to move said closure element into, and hold it in, position closing said orifice, an intermittently driven element, means operated by said intermittently driven element for moving said closure element to open said orifice, and coupling and uncoupling means controlled by the variations in the degree of resistance offered to the movement of said driven means in said tank whereby when said resistance equals the applied power of said source of energy said driven element will be coupled to said drive element and driven thereby to move said closure element to open position and when said resistance drops below said applied power said driven element will be uncoupled from said drive element and said source of energy will act to move said closure element to closed position and hold it in such position until the applied power of said source of energy is again equaled by said resistance.

CHARLES HARRELL.
